OVEN CONSTRUCTION

Robert E. Shay, Marblehead, and Sandford C. Peek, Jr., Salem, Mass., assignors to Sylvania Electric Products Inc., Salem, Mass., a corporation of Massachusetts

Application December 13, 1950, Serial No. 200,622

4 Claims. (Cl. 13-6)

1

This invention relates to heating apparatus and more particularly to an oven for heating elongated vitreous articles such as linear fluorescent tubes.

In the manufacture of circular fluorescent lamps from linear glass tubes, a proper heating of the tubes to permit satisfactory fabrication to a circular configuration is a most important consideration. The linear glass tubes should be heated to a plastic condition and elongation thereof permitted to occur before fabrication to a circular configuration is attempted. On the other hand, care must be exercised to prevent the tubes from being heated to a point where control of their shape may be lost. Since the temperature range between sufficient heating and excessive heating is not very great, considerable care must be exercised to heat the tubes to a degree of heat which falls within this range. The heating problem is rendered more difficult by the configuration of the article being heated since it is a long slender tube, the length of which is many times greater than its diameter.

An object of our invention is to heat elongated vitreous articles uniformly to a plastic condition.

The oven of our invention comprises a pair of wall members, the inner faces of which are provided with a plurality of radiant heating elements, and a convection heating element disposed at the base thereof. The flue gases from the convection heating element provide a circulation of hot air about and along the length of the articles, thereby rendering the temperature of the articles substantially uniform along their entire length.

A specific embodiment of the oven of our invention is illustrated in the accompanying drawings in which:

Figure 1 is a plan view partly in section of an apparatus for bending linear fluorescent lamps into circular shape, with which an oven embodying our invention may be employed.

Figure 2 is a sectional elevational view taken along the line 2-2 of Figure 1 showing the relation of an oven with respect to the turret of the machine.

Figure 3 is a longitudinal sectional view of an embodiment of the oven of our invention.

Figure 4 is a transverse sectional view of the oven taken along the line 4-4 of Figure 3 and showing the oven in the closed position.

Figure 5 is a transverse sectional view taken along the line 5-5 of Figure 3 and showing the oven in the open position.

Figure 6 is a longitudinal sectional view of a convection heating element.

2

Referring now to the specific embodiment of the invention illustrated in the drawings, particularly Figures 1 and 2 thereof, a linear fluorescent lamp 1, held by a lamp holder 2, and seated on a lamp support 3, is carried through a plurality of work stations at which the lamp is heated and finally fabricated to the desired configuration. Movement of the lamp 1 through a plurality of work stations is effected on a rotatable turret type machine in which a plurality of lamp holders 2 and lamp supports 3 are mounted on a turret 4. The turret 4 comprises an upper ring plate 5, about the periphery of which the plurality of lamp holders 2 are mounted; a lower ring plate 6, about the periphery of which the plurality of lamp supports 3 are mounted; supporting columns 7 depending from the upper ring plate 5, to the other ends of which the lower ring plate 6 is attached; and a spider 8 attached to the top of the upper ring plate 5. Rotation of the turret 4 is effected by a vertical drive shaft 9 upstanding on a pedestal 14. The shaft 9 is driven by a gear 17 which is connected to a suitable drive mechanism (not shown). The shaft 9 extends through a base 11 and is journaled in the hub of the spider 8. The shaft 9 is maintained in a true vertical position by a thrust bearing 10 and a plurality of guides 12 upstanding from the base 11. The base 11 is mounted on legs 13 upstanding on the pedestal 14. Stability is imparted to the turret 4, particularly the lower ring plate 6 thereof, by rollers 15 mounted on the tops of posts 16 mounted on the base 11. These rollers 15 engage the inside face of the lower ring plate 6 and aid in insuring true circular rotational movement of the turret 4.

Referring to Figures 1 and 2, heating of the linear fluorescent lamp 1 is effected in several separate ovens 59 disposed at work stations adjacent to the periphery of the turret 4. Each oven 59 comprises a pair of semi-circular members 60 and 61 which define a heating chamber, circular in cross-section, within which the lamp 1 is heated. Each oven 59 is supported from a carriage 69 by two pairs of arms 70 and 71, and 72 and 73 mounted on a vertical supporting shaft 74 upstanding on the carriage 69. Arms 70 and 72 are connected to oven member 60 and arms 71 and 73 are connected to oven member 61. Actuation of oven members 60 and 61 to open and close them with reference to one another is effected by the reciprocating motion of piston rod 76 of air cylinder 86, mounted on a shelf 75 on carriage 69. The source of air which actuates the piston rod 76 and the connection therebe-

tween have not been shown since a suitable conventional arrangement may be employed. The piston rod 76 of the air cylinder 86 has a link guide 25 (Figures 4 and 5) attached to the outside end thereof. The link guide 25 has a pair of slots 26 cut therein, through which pins 27 upstanding on one end of levers 78 and 79 extend. The levers 78 and 79 are mounted intermediate their ends on the supporting shaft 74, the other ends thereof being connected to oven members 60 and 61 respectively.

The carriage 69 is mounted on wheels 80 which ride on tracks 81 on carriage support 82. Reciprocating movement of the carriage 69 on the tracks 81 is effected by the reciprocating motion of air cylinder 83 mounted on the carriage 69. The source of air which actuates the air cylinder 83 and the connection therebetween have not been shown since a suitable conventional arrangement may be employed. The outer end of the piston rod 84 of air cylinder 83 is fixed in a bracket 85 mounted on the carriage support 82. Thus when air cylinder 83 is actuated it moves along its fixed piston rod 84 and carries the carriage 69, on which it is mounted, with it.

Referring to Figures 2, 3, 4 and 5, each oven 59, as was mentioned above, comprises a pair of semi-circular members 60 and 61. Each of the members 60 and 61 comprises a metal body member 28, to which the levers 78 and 79 are attached, an inside wall 29 of insulating material and an outside wall 30 of insulating material. The inside wall 29 of each of the members 60 and 61 is provided with a plurality of separate radiant heating elements, such as electric heating elements 62 for example, disposed along the longitudinal axis thereof and connected to a source of electrical energy (not shown). Each of the members 60 and 61 is cut away at 63 and 64 to permit entrance of a portion of the lampholder 2 and the lamp support 3 when the carriage 69 moves the ovens 59 inwardly to envelop the lamps.

A convection heating element, such as cone-type gas burner 65, is disposed inside the oven near the base thereof and is supported by a bracket 66 attached to the bottom of member 61 of oven 59. As may be seen in Figure 6, the burner 65 comprises a frame 67, a tunnel 31 mounted thereon, and a tip 32 seated in an aperture therefor in the frame 67 and disposed at the base of the tunnel 31. A flexible hose 68, attached to the frame 67, is connected to a gas supply (not shown).

The combination of a plurality of separate radiant heating elements 62 spaced from one another along the longitudinal axis of the oven 59 and a convection heating element 65 mounted near the base thereof and in register with but spaced from the bottom end of the lamp, provides a heating apparatus which heats the lamp uniformly to a plastic condition. A plurality of separate heating elements 62, each of which is provided with separate controls, enables adjustments to be made in the amount of heat being supplied at several areas along the longitudinal axis of the lamp. Disposition of the gas burner 65 near the lower end of the lamp 1 but spaced therefrom provides a source of hot gases which flow upwardly enveloping the lamp and thereby assisting in developing and maintaining uniform heating of the lamp.

In order to protect the electric heating elements 62 from pieces of a lamp which may accidentally break in the oven, a grill 33 is disposed between the heating elements 62 and the lamp 1.

Although only one such grille 33 is shown in Figure 3, additional grilles to protect the other heating elements 62 may be employed.

After the linear lamp 1 has been heated in the last oven 59, it is moved to the lamp rolling station where it is formed into circular configuration by a roller 87. The lamp roller 87 comprises a pair of cooperating discs 88 and 89, which, when the adjacent faces thereof are brought into engagement with one another, define a mould 90 in their peripheries. Discs 88 and 89 are supported by a yoke 91 through shafts 92 and 93 respectively. The yoke 91 has a pair of bosses 98 formed in the sides thereof through which yoke-guiding columns 99 mounted on pedestal 14, extend. Actuations of the yoke 91 to effect movement thereof up and down on the columns 99 is effected by an air cylinder 94 (connected to a source of air under pressure, not shown) mounted on pedestal 14. The piston rod of the air cylinder 94 is connected to the yoke 91 through a rod 96, supported at its ends in a pair of rod supports 97 mounted on the sides of the yoke.

In their inoperative position, the discs 88 and 89, which comprise the lamp roller 87, normally are spaced from one another to permit movement of the lamp 1 into operative position. Closing of the discs 88 and 89 to their operative position as shown in Figure 1 is effected by means of an air cylinder 103 (connected to a source of air under pressure, not shown) mounted on a bracket 104 on a side of the yoke 91. The piston rod 105 of the air cylinder 103 is connected through a rack 106, a gear 107, and a suitable linkage mechanism to levers 117 and 118. The levers 117 and 118 are pivotally mounted intermediate their ends in the sides of yoke 91 and their other ends are pivotally connected to hubs 121 and 122 on discs 88 and 89 respectively.

Upon completion of the lamp rolling operation the lamp is then cooled at succeeding stations on the machine and finally removed.

That portion of the apparatus for fabricating the linear lamp to the desired configuration, which is shown and described herein in connection with the oven of our invention, is the subject matter of the co-pending application of Sandford C. Peek, Jr., et al., entitled "Apparatus for Bending Linear Glass Tubing," filed of even date herewith.

What we claim is:

1. An oven for heating elongated vitreous articles comprising: a pair of wall members of insulating material disposed in a vertical plane; a plurality of separate radiant heating elements spaced from one another longitudinally along the longitudinal axis of said wall members and disposed adjacent to but spaced from the inner faces thereof; and a convection heating element disposed within the space defined by said wall members and located near the lower longitudinal ends thereof.

2. An oven for heating elongated vitreous articles comprising: a pair of wall members of insulating material disposed in a vertical plane; a plurality of separate electric heating elements spaced from one another longitudinally along the longitudinal axis of said wall members and disposed adjacent to but spaced from the inner faces thereof; and a gas burner disposed within the space defined by said wall members and located near the lower longitudinal ends thereof.

3. An oven for heating elongated vitreous articles comprising: a pair of wall members of insulating material disposed in a vertical plane; a plu-

rality of separate radiant heating elements spaced from one another longitudinally along the longitudinal axis of said wall members and disposed adjacent to but spaced from the inner faces thereof; a bracket attached to the bottom of one of said wall members; and a gas burner mounted on said bracket and disposed within the space defined by said wall members.

4. An oven for heating elongated vitreous articles comprising: a pair of wall members of insulating material disposed in a vertical plane; a plurality of separate radiant heating elements spaced from one another longitudinally along the longitudinal axis of said wall members and disposed adjacent to but spaced from the inner faces thereof; a grille mounted on said wall members and disposed in front of and spaced from said heating elements; and a convection heating element disposed within the space defined by said

5

wall members and located near the lower longitudinal ends thereof.
